[73] Assignee: **Ecolab, Inc.**, St. Paul, Minn.

[57] CLAIM

[**] Term: **14 Years**

The ornamental design for bi-lobal solid block machine detergent, as shown and described.

[21] Appl. No.: **82,046**

DESCRIPTION

[22] Filed: **Jan. 13, 1998**

FIG. 1 is a perspective view of the bi-lobal solid block machine detergent of the present invention;

Related U.S. Application Data

FIG. 2 is an top plan of the bi-lobal solid block machine detergent of the present invention;

[63] Continuation-in-part of Ser. No. 781,493, Jan. 13, 1997.

FIG. 3 is a front elevation of the bi-lobal solid block machine detergent of the present invention; and,

[51] LOC (6) Cl. **23-01**

FIG. 4 is a side elevation of the bi-lobal solid block machine detergent of the present invention.

[52] U.S. Cl. **D23/207**

[58] **Field of Search** D23/207, 200;
D23/208; D24/101, 102, 103; D28/8.1;
424/464; D13/100; 510/142
